13 Claims. (Cl. 96—67)

This invention relates to light-sensitive photographic material and particularly to direct positive photographic material.

It is known that, if a photographic silver halide emulsion, which has been exposed to blue light, is subsequently exposed to long-wave radiation before it is developed, the effect of the original exposure is partly destroyed. This is known under the name of Herschel-effect and may be used for obtaining a reversed image.

It is also known that desensitizing dyes may be added to the emulsion in order to increase the Herschel-effect.

Thus it is known to produce a direct positive emulsion by incorporating in a silver chloride emulsion, which is substantially free from silver bromide or silver iodide, a proportion of compounds having a nitro group attached to a benzene nucleus, such compounds being selected from benzthiazole, quinoline, indolenine, benztriazole and rhodanine compounds and their alkyl quaternary salts, and fogging the emulsion by light or chemical means.

It is further known that direct positive emulsions may be produced by using a compound according to the general formula

wherein A=a quaternary heterocyclic cinnoline or quinazoline nucleus.

The use of rhodium halide in direct positive emulsions has been described in British specification No. 707,704.

It is an object of the present invention to provide a new direct positive photographic material.

Another object of this invention is to provide a method for making new photographic materials suitable for inversion according to the Herschel-effect.

Other objects of this invention will become apparent from the following description and examples.

We have found that direct positive emulsions of high quality may be produced by the general technique described hereinbefore, by using a compound according to one of the tautomeric formulae

and

2

wherein

A=a member selected from the group consisting of a single bond and —NH—,

B=a member selected from the group consisting of aryl substituted with at least one nitro group, arylene symmetrically substituted by at least one nitro group, and arylene-SO₂-arylene substituted symmetrically by at least two nitro groups, the arylene and arylene-SO₂-arylene groups constituting the centre of a symmetrical compound containing two dihydropyrimidine nuclei of one of the above tautomeric formulae,

R₁=a member selected from the group consisting of hydrogen, hydroxyl, alkyl, aralkyl and aryl,

R₂=a member selected from the group consisting of hydrogen, alkyl, aralkyl and aryl,

R₃=a member selected from the group consisting of hydrogen, alkyl, aralkyl and aryl.

The compounds may be incorporated in silver chloride, silver chloro-iodide or silver chloro-bromide emulsions. The optimum amount is between 25 mg. and 7.5 g. per equivalent of 100 g. silver nitrate.

The compounds according to the present invention may also be added to a layer which is adjacent to the emulsion. In general, the same amounts per square metre are used. The emulsion is prefogged by light or chemical means, for example by formaldehyde or stannous chloride.

The following examples are intended to illustrate the present invention without limiting, however, the scope thereof:

Example 1

30 200 ml. of a 0.5% solution in ethyl alcohol of the compound according to the formula

low precipitate is formed. After cooling, the precipitate is sucked off. The product melts at 196-197° C.

Example 2

4 kg. of a silver chloro-bromide emulsion (5% bromide) containing the equivalent of 100 g. silver nitrate are heated to 40° C. and the pH adjusted to 8. Eight ml. of an aqueous solution of formaldehyde (40%) are added and the emulsion is kept at the same temperature for 10 minutes. The pH is adjusted to 6, and 120 ml. of a 0.5% solution in dioxane of the compound according to the formula

are added. The emulsion is then coated on a film support. This chemically fogged emulsion is exposed to an image through a Gevalor filter L 500.

The product of the formula last above given is prepared as follows: 47.42 g. 2-4-dinitrophenylhydrazine are dissolved in 600 ml. dioxane, 39 g. 2-methyl-2-thiocyanopropenone are added and the whole is refluxed for 3 hours. After cooling, the solution is poured in water, the precipitate is sucked off and washed with water and cold ethyl alcohol. The precipitate is further washed with 500 ml. hydrochloric acid (2 N) whilst stirring, and finally with water. The product melts, after recrystallization in acetic acid, at 215-217° C.

Example 3

A gelatin upper layer (1.5% gelatin) whereto previously 100 ml. per litre of a 0.5% solution in diacetone alcohol of the compound according to the formula

are added, is coated on a silver chloro-iodide emulsion (1% iodide) containing the equivalent of 20 g. silver nitrate per kg. The obtained photographic material is further treated as in Example 1.

The product according to the formula last above given is prepared as follows: 3.3 g. beta-amino-hydrocinnamic acid are dissolved in a solution of 0.8 g. sodium hydroxide in 100 ml. water. Next, 3.96 g. p-nitrophenyl-isothiocyanate dissolved in 30 ml. acetone are added. After 3 hours' stirring at room temperature, a yellow precipitate is obtained. After filtrating and acidifying the filtrate with hydrochloric acid (2 N), a solidifying yellow oil is obtained. After recrystallization in ethyl alcohol, a product according to the formula

is obtained, which melts at 156-157° C. 3.5 g. of this product are heated in 160 ml. hydrochloric acid (2 N)

40 for 3 hours at the boiling water bath. It does not dissolve but forms small white flocks. After cooling, sucking off and recrystallizing in acetic acid, it melts at 248-250° C.

Example 4

100 ml. of a 0.5% solution in diacetone alcohol of the compound according to the formula

are added to 1 kg. silver chloride emulsion containing the equivalent of 20 g. silver nitrate. Next, the emulsion is coated on a paper support and further treated as in Example 1.

The product according to the formula last above given is prepared as follows: to a solution of 3.6 g. p-nitrophenyl-isothiocyanate in 20 ml. benzene, a solution of 1.68 g. beta-amino-butyric acid nitrile in 10 ml. benzene is added. After 30 minutes heating on the boiling water bath, the formed oil solidifies. After cooling, sucking off and recrystallizing in ethyl alcohol, a product according to the formula

is obtained which melts at 138-139° C. 3.2 g. of this product are refluxed for 90 minutes in 30 ml. strong hydrochloric acid. First the whole dissolves and after some time boiling a precipitate is formed. After cooling, sucking off and recrystallizing in acetic acid, the desired product is obtained under the form of small white needles melting at 237-239° C.

Example 5

50 ml. of a 0.5% solution in dioxane of the compound according to the formula

are added to 1 kg. silver chloride emulsion containing the equivalent of 25 g. silver nitrate. Next, the emulsion is coated on a paper support. The photographic material obtained is further treated as in Example 1.

The product according to the formula last above given is prepared as follows: 1.2 g. picryl hydrazine are dissolved in 60 ml. hydrochloric acid (5 N). Next, 0.78 g. 2-methyl-2-thiocyanopropenone-(4) are added. The whole is boiled for 1 hour. After cooling, and standing overnight, the obtained product is sucked off, washed with water and recrystallized in acetic acid.

Example 6

70 4 kg. of a silver chloro-bromide emulsion (10% bromide) containing the equivalent of 20 g. silver nitrate per kg. are heated to 40° C. and brought at a pH of 8. Next, 8 ml. of an aqueous solution of formaldehyde (40%) are added and the emulsion is kept for 10 minutes at the same temperature. The pH is brought at 6

and 100 ml. of a 0.5% solution in diactone alcohol of the product according to the formula

are added. Then, the emulsion is coated on a film support. This chemically fogged emulsion is exposed to an image through a Gevalor filter L 500. 15

The product according to the formula last above given can be prepared as follows: 5.2 g. of the product according to the formula

are heated for 6 hours with 4.76 g. 2-methyl-2-thiocyanopentanone in 300 ml. hydrochloric acid (2 N). The orange precipitate obtained is cooled, washed with hydrochloric acid (2 N), water, ethyl alcohol and ether respectively, and extracted with ethyl alcohol until the latter remains colourless. The product obtained melts at 256-258° C.

Example 7

A gelatin upper layer (1.5% gelatin) to which previously 200 ml. per litre of a 0.5% solution in diacetone alcohol of the compound corresponding to formula 35

were added, is coated on a silver chloro-iodide emulsion (0.1% iodide) containing the equivalent of 20 g. silver nitrate per kg. The photographic material obtained is further treated as in Example 1.

The product of the formula last above given is prepared as follows: 4.56 g. 1-3-dinitro-4-6-hydrazino benzene are heated in 150 ml. water for 4 hours on the boiling water bath with 6.28 g. 2-methyl-2-thiocyanato-4-pentanone. After cooling and sucking off, the product obtained is washed with water, hydrochloric acid (2 N), water, ethyl alcohol and ether respectively. After recrystallization in acetic acid, the obtained product melts at 223-224° C.

at 223-224

We claim:

1. A direct positive silver halide photographic material comprising a silver halide emulsion layer and a gelatin layer adjacent thereto, the gelatin layer containing the product of the formula

2. A direct positive photographic material comprising

2. If there are no photographs, then the following
should be done: (a) take a photograph of the
specimen, (b) draw a sketch of the specimen, (c) take
a photograph of the label, (d) take a photograph of
the specimen and the label together.

CH₃   3. A direct positive silver halide photographic material comprising a silver halide emulsion layer and a gelatin layer adjacent thereto, the gelatin layer containing the product of the formula

4. A direct positive photographic material comprising a silver halide emulsion containing the product of the formula

5. A direct positive silver halide photographic material comprising a silver halide emulsion layer and a gelatin layer adjacent thereto, the gelatin layer containing the product of the formula

6. A direct positive photographic material comprising a silver halide emulsion containing the product of the formula

75. A direct positive silver halide photographic mate-

trial comprising a silver halide emulsion layer and a gelatin layer adjacent thereto, the gelatin layer containing the product of the formula

8. A direct positive photographic material comprising a silver halide emulsion containing the product of the formula

9. A direct positive silver halide photographic material comprising a silver halide emulsion layer and a gelatin layer adjacent thereto, the gelatin layer containing the product of the formula

10. A direct positive silver halide photographic material comprising an unsensitive gelatin layer adjacent to the silver halide emulsion, said layer containing the product of the formula

11. A direct positive silver halide photographic material comprising a silver halide emulsion layer and a gelatin layer adjacent thereto, at least one of said layers containing a compound selected from the group consisting of compounds corresponding to one of the tautomeric formulae:

and symmetrical compounds corresponding to one of the tautomeric formulae:

in which four formulae A represents a member selected from the group consisting of a single bond and $-\text{NH}-$, B represents an aryl radical substituted with at least one nitro group, D represents a member selected from the group consisting of an arylene radical substituted with at least one nitro group, and an arylene- SO_2 -arylene radical, each arylene group of which is substituted with at least one nitro group, R₁ and R₂ each represents a member selected from the group consisting of a hydroxyl radical and an alkyl radical, and R₃ represents a member selected from the group consisting of a hydrogen atom, an alkyl radical, and an aryl radical.

12. A direct positive silver halide photographic emulsion characterized by the presence in the emulsion of a compound selected from the group consisting of compounds corresponding to one of the tautomeric formulae:

and symmetrical compounds corresponding to one of the tautomeric formulae:

and

60 in which four formulae A represents a member selected from the group consisting of a single bond and $-\text{NH}-$, B represents an aryl radical substituted with at least one nitro group, D represents a member selected from the group consisting of an arylene radical substituted with at least one nitro group, and an arylene- SO_2 -arylene radical, each arylene group of which is substituted with at least one nitro group, R₁ and R₂ each represents a member selected from the group consisting of a hydroxyl radical and an alkyl radical, and R₃ represents a member selected from the group consisting of a hydrogen atom, an alkyl radical, and an aryl radical.

65 13. A direct positive silver halide photographic material characterized by the presence in a layer adjacent to the silver halide emulsion of a compound selected from

70 75

the group consisting of compounds corresponding to one of the tautomeric formulae:

and symmetrical compounds corresponding to one of the tautomeric formulae:

and

in which four formulae A represents a member selected from the group consisting of a single bond and —NH—, B represents an aryl radical substituted with at least one nitro group, D represents a member selected from the group consisting of an arylene radical substituted with at least one nitro group, and an arylene-SO₂-arylene radical, each arylene group of which is substituted with at least one nitro group, R₁ and R₂ each represents a member selected from the group consisting of a hydroxyl radical and an alkyl radical, and R₃ represents a member selected from the group consisting of a hydrogen atom, an alkyl radical, and an aryl radical.
